J. G. SIMMONS

INSULATOR CHANGER

Filed Aug. 13, 1923

INVENTOR.
BY *John G. Simmone,*
William A. Smith, Jr.
ATTORNEY.

UNITED STATES PATENT OFFICE.

JOHN GILBERT SIMMONS, OF MARION, ILLINOIS.

INSULATOR CHANGER.

Application filed August 13, 1923. Serial No. 657,158.

My invention relates to insulator changers and has particular reference to an improved portable device adapted for use by linemen to assist in the replacement and repair of damaged insulators on high tension electric transmission lines.

It is to be understood that overhead electric systems for the transmission and distribution of high tension electric currents usually comprise a system of poles or towers each provided with upper cross-arms carrying at opposite sides of the pole one or more insulators on which are supported and attached the line wires of the system. These insulators are generally made of glass, porcelain, or other non-conducting material and due to their construction, conditions of use and varying climatic conditions, these insulators become cracked or broken and require frequent replacement and repair. It has heretofore been customary, when it is desired to repair or replace a defective or damaged insulator, to cut off the current in the line wires to enable the linemen to handle the line wire without danger of injury; but such interruption of current is not desirable and is to be avoided if possible.

It is an object of my invention to provide an insulator changer comprising means for temporarily supporting the line wires of high tension transmission lines in such a manner that the lineman may safely and conveniently repair or replace the defective or damaged insulator without the necessity of cutting off the current passing through the line wire.

A further object of my invention is to provide an insulator changer capable of ready attachment to the supporting pole or tower on which the damaged insulator is located, and which, by proper manipulation, will temporarily support and maintain the line wire out of engagement with the insulator to enable the lineman to safely repair or replace the same without danger of injury and without the necessity of interrupting the current passing through the line wire.

A further object of my invention is to provide a device of the above mentioned character that is simple in construction, inexpensive to manufacture, strong and durable, and highly efficient and convenient in the purposes for which designed.

In the accompanying drawings, forming a part of this specification, and in which like

numerals are employed to designate like parts throughout the several views;

Figure 1 is an elevation of a supporting pole for high tension transmission lines, showing my improved insulator changer attached and in position to temporarily support the line wire;

Figure 2 is a sectional view on the line 2-2 of Figure 1;

Figure 3 is a sectional view of the line 65 wire engaging end of the lifting pole; and

Figure 4 is a sectional view on the line 4-4 of Figure 2.

Referring to the drawings, wherein for the purpose of illustration is shown a preferred example of my invention, the numeral 5 designates a pole such as commonly used on high tension transmission lines, said pole being provided near its upper end with transverse cross arms 6 strengthened by suitable diagonal supports 7. At opposite sides of the pole 5, each of said cross arms is provided with one or more insulators 8 upon which are supported and fastened the line wires 9. All of the above construction is old 80 and well known in the art and constitutes no part of my present invention.

My improved insulator changer comprises a lifting pole 10, preferably formed of wood or other non-conducting material, and having at its upper extremity a wire engaging clamp 11, adapted to be opened or closed by axial rotation of the pole. The pole 10 is slidably and pivotally mounted within a clamping member 12, swiveled at one end of 90 a transverse bar or section 13.

The section 13 has a depending perpendicular portion 14 and a segmental portion 15, which is provided with a longitudinal series of holes or passages 16 for bolts or pins, 95 serving a purpose to be hereinafter described. The section 13 further carries second perpendicular and segmental portions 14' and 15' respectively, held in parallel spaced relation to the sections 14 and 15 by 100 the connecting webs or sections 17, of a length slightly greater than the diameter of the lifting pole 10. The segmental section 15' is also provided with a series of longitudinal holes or passages 16' which register 105 with the holes or passages 16 in the segmental section 15.

The pole engaging member of my improved device comprises a pair of co-acting semi-circular metal straps 18 and 19, hav- 110

ing outwardly extending end portions 20 and 21, each provided with openings through which may be passed the clamping bolts 22. The inner surface of these straps 18 and 19 5 may be provided with inwardly projecting spurs 23 which assist in maintaining the device in its adjusted position upon the pole. The transverse section 13 is secured to the metal strap 19 by means of suitable rivets 10 or bolts 25.

Referring to the operation of my improved device, and assuming that it is desired to replace or repair a defective or damaged insulator without the necessity of interrupting the current flowing through the line, the segmental sections 18 and 19 are placed in appropriate position about the pole 5 and securely fastened thereto by means of the clamping bolts 22. The lifting pole 10, which has been previously passed through the clamp 12 and between the parallel sections 14 and 14' and 15 and 15', is then manipulated until the wire engaging end 11 is brought into engagement 20 with the line wire 9, and is clamped securely thereto by axial rotation of the pole 10. The lifting pole 10 is then forced upwardly until the line wire 9 is clear of the insulator 8 and the clamp 12 is then tightened to securely maintain the pole in its extended position. The pole 10 is then moved about the pivot of the clamp 12 as clearly shown in dotted lines in Fig. 1, until the line wire is entirely away from the insulator 8, thus 30 leaving room for the lineman to remove and replace the insulator without any danger of contact with the current-carrying line wire. When the line wire 9 has been moved sufficiently to one side of the insulator to enable the lineman to safely remove the same, pins or bolts 24 are inserted on opposite sides of the pole 10, through adjacent holes or passages 16 and 16' in the segments 15 and 15' which securely hold the pole against 40 movement about the pivot of the clamp 12. It is also to be observed that the extensions 20 and 21 form a substantial and convenient standing place upon which the lineman may stand while changing the insulator. 45 After the damaged or defective insulator has been replaced the pins or bolts 24 are removed, the clamp 12 released or loosened and the line wire returned and fastened to the insulator. It is thus obvious that I 50 have provided an efficient apparatus for ac-

complishing the purposes set forth and one that will materially expedite and make safe the changing of insulators.

It is to be understood that the form of my invention herein shown and described is to be taken as a preferred embodiment of the same, and that various changes in the size, shape and arrangement of parts may be resorted to without departing from the spirit of my invention or the scope of the sub- 60 joined claims.

Having thus described the invention, I claim:

1. An insulator changer for high tension transmission lines, comprising a support 70 temporarily connected to a pole, spaced parallel sections carried by the support, a lifting pole pivotally mounted on said support and extending between said parallel sections, means carried by said lifting pole for engaging and holding the line wire, and means carried by the parallel sections for maintaining said lifting pole in an adjusted position about its pivotal mounting. 75

2. An insulator changer for high tension transmission lines, comprising a support temporarily connected to a pole, spaced parallel sections carried by said support, a lifting pole slidably and pivotally mounted on said support, and extending between said parallel sections, means carried by said lifting pole for engaging and holding the line wire, means for maintaining said lifting pole in extended position, and means carried by said parallel sections for maintaining the 85 lifting pole in an adjusted position about its pivotal mounting. 90

3. An insulator changer for high tension transmission lines comprising a support adapted to be temporarily secured to a pole, 95 spaced parallel sections carried by said support and having a series of spaced registering openings, a lifting pole pivotally mounted on said support and extending between said parallel sections, means carried by said lifting pole for engaging and holding the line wire, and pins inserted in the holes of said parallel sections on opposite sides of said lifting pole to maintain the lifting pole in an adjusted position about its pivotal 100 mounting. 105

In testimony whereof I hereunto affix my signature.

JOHN GILBERT SIMMONS.
